Application August 7, 1943, Serial No. 497,738

9 Claims. (Cl. 101—252)

This invention relates to improvements in printing machines.

The main objects of this invention are:

First, to provide a novel and improved method for printing indirect or offset impressions from a relief or letter press form.

Second, to provide a printing method of the type described for offset printing from a conventional type form in which the final impression is characterized by its clarity and sharpness and in which the need for make-ready, patching and like work is eliminated.

Third, to provide a machine for producing offset printing impressions from a letter press or relief type form or relief printing surface in which the form is quickly and easily set up and impressions produced therefrom without requiring extensive preliminary work, make-ready, patching and the like.

Fourth, to provide a flat bed or bed and cylinder machine adapted to print offset impressions from a form of the type described.

Fifth, to provide a combination of offset or transfer members or surfaces, a printing form, inking mechanism and a printing cylinder for printing offset impressions of the type described which is well adapted for incorporation in known types of flat bed or bed and cylinder printing machines.

Further objects relating to details and economies of the invention will appear from the description to follow. The invention is defined in the claims.

A structure embodying the features of this invention is illustrated in the accompanying drawings, wherein:

Fig. 1 is a perspective view illustrating a printing machine suitable for performing the method of the invention, certain parts of the sheet feeding mechanism having been removed to clarify the arrangement of parts of the press.

Fig. 2 is an enlarged, fragmentary, perspective view from the side of the press opposite that shown in Fig. 1, further illustrating certain features thereof embodied in the invention.

Fig. 3 is a fragmentary top plan view of the press according to the invention, certain parts thereof not germane to the invention having been removed in order to facilitate an understanding of the structure of the press and the printing method performed thereby.

Fig. 4 is an enlarged, fragmentary view in vertical section, on line 4—4 of Fig. 3, longitudinally of the press illustrating the operating connections therewith.

Figs. 5 and 6 are enlarged, fragmentary views illustrating diagrammatically the operation of the present press in opposite relative movements of the bed and printing cylinders thereof.

Fig. 7 is a fragmentary view in side elevation illustrating the cylinder elevation control instrumentalities incorporated in the press.

Fig. 8 is a fragmentary conventional view illustrating the layout in coacting relation with the roll lowering means.

This invention relates generally to a method of printing an indirect or offset impression from an ordinary letter press or relief type form, and to a flat bed or bed and cylinder rolling contact press for performing the invention. It will be understood that ordinary printer's type face is negative or reversed, as are of course all ordinary relief printing plates employed in relief printing processes. This of course prints a positive impression.

The present invention contemplates a method and apparatus for producing a positive impression from such a relief or letter press form by offset printing and the method and apparatus to be hereinafter described have provision for enabling this to be done without extensive preliminary work, make-ready, patching and the like. Moreover, the final printed impressions are characterized by uniform clarity and sharpness, and such uniformly sharp impressions are possible regardless of slight differences in the elevation of various parts of the original printing surface. The provisions for performing the method of the invention are well adapted for incorporation in a well known type of rolling contact bed and cylinder machine with certain changes therein.

In the drawings, wherein there is illustrated a horizontal reciprocating flat bed type machine suitable for the purposes of the invention, the reference numeral 1 in general indicates a frame provided with spaced, parallel, horizontal ways in which a flat reciprocable bed 2 is slidably mounted (Fig. 4). The frame has a superstructure 3 extending above the same providing secondary ways in which the roller carriage 4 is likewise mounted for horizontal, reciprocatory, sliding movement. There is not illustrated in detail the way or guide structure for mounting the bed and carriage for the movements described, inasmuch as presses having provisions to this end are well known. It will suffice to say that the movements of the bed, which carries the original type form, a transfer surface and an inking surface, to be hereinafter described,

move simultaneously with and oppositely of the cylinder carriage 4. Both the bed and carriage are preferably reciprocated for the purpose of reducing the throw of the parts and increasing the speed of printing. However, it will be appreciated that, if desired and if space and speed requirements were no object, only one of the members need be reciprocated for movement relative to the other.

Referring to Fig. 4, the reference numeral 5 designates a conventional inking structure including a fountain 6 and fountain roll 7 journaled relative thereto. This roll is intermittently rotated during the operation of the press by a conventional linkage not necessary to describe in detail. For coaction with the roller there is provided a ductor 8 which is pivoted on the frame at 9. The ductor is oscillated to and from the fountain roll to apply ink to a flat inking plate 10 carried by bed 2 in the reciprocation thereof. The bed also has suitably locked thereon by means of blocks, quoins and the like, a letter press printing form 11 of the character referred to above and an offset or transfer member 12 having a flat resilient offset surface 13, to be hereinafter referred to. The printing form 11 and transfer member 12 are mounted on the bed in spaced relation longitudinally of the press as illustrated in Fig. 4, the bed being illustrated in its extreme lefthand position in that figure.

Form 11 receives ink from the inking plate 10 by means of a pair of form inking rollers 14 journaled in a suitable reciprocating carriage 15 which is slidably mounted on the press frame in an appropriate manner. Rollers 14 pick up ink from plate 10 by rolling thereacross, and the ink is distributed on rollers 14 by means of a reciprocating vibrator roller 16 which is journaled in frame 15 and rides on rollers 14. Roller 16 is vibrated longitudinally of rollers 14 and transversely of the press by means of any well known reciprocating device. The ink deposited on inking plate 10 by ductor 8 is worked up and distributed thereon by a pair of angled distributor rollers 17 mounted in forks on the frame.

Prior to further describing the printing operation in detail, the mechanism for producing the operative movements of the various reciprocating parts of the press will be explained. This structure is illustrated in Fig. 4. The reference numeral 18 designates a pulley appropriately journaled on the frame and driven by a belt 19 from a further pulley on the shaft of a suitable motor 190, likewise mounted on the frame. Pulley 18 rotates shaft 20, to which is secured a pinion 21 meshing with a large gear 22 journaled on the frame. This gear rotates a shaft 23 on which is secured a crank 24, said crank being drivingly connected by means of a rearwardly extending connecting rod 25 with an oscillating pitman 26 which is pivoted at 27 to the frame. At its upper end the pitman is drivingly connected to the bed 2 by means of a drive link 28 pivoted at its opposite ends to a depending bracket 29 on the bed and to the extremity of the pitman.

At an intermediate point the pitman has pivoted thereon a rearwardly extending arm 30 which at its free end is pivotally connected to a bracket 31 secured to and depending downwardly from a slide 32. This slide is mounted by anti-friction rollers 33 on the frame 322 of the press for reciprocating movement longitudinally of the latter and carries at its rear end an

inclined cam element 34 which is engageable with a roller 35 on an arm 36 secured to the ductor roll supporting arm 381. Accordingly, as the cam and roller engage, the ductor 8 will be swung from the fountain roller 7 forwardly into engagement with the inking plate 10 to deposit a quantity of ink on the latter.

Intermediate the mid-point of pitman 26 and the pivot 27 thereof the latter has rearwardly extending connecting rod or link 37 pivoted thereto, the extreme end of this connecting rod being in turn pivoted to the downwardly extending end 38 of the lever 39 which is pivoted on the frame at 40. Lever 39 extends upwardly and at its upper extremity pivotally carries a forwardly extending link 41 which is pivoted to the inking roller carriage 15. Accordingly as pitman 26 is oscillated by crank 24 and connecting rod 25, it will be appreciated that the bed 2 and slide 32 are reciprocated simultaneously in the same direction, and that the form inking roller carriage 15 will be reciprocated in the opposite direction to pick up ink from plate 10 traveling therebeneath and apply the same to the form 11. The magnitude or amplitude of the reciprocable movement of carriage 15 is much less than that of the bed, because of the greater arc of swing of pitman 26 at the bed connection than at the inking roller carriage connection.

For producing reciprocation of the cylinder carriage 4 simultaneous with the reciprocation of bed 2 but in the opposite direction an arrangement is utilized generally similar to that illustrated and described in the patent to Vierengel, No. 1,072,883, of September 9, 1913. This is not shown herein in great detail, but consists of an elongated rack 42 carried by and reciprocable with the bed on the frame (and effective to rotate the two printing cylinders to be hereinafter described). A rack 42 is provided at either side of the bed and these racks mesh with gears 43 mounted on a shaft 44 which is rotatably journaled at 44' in the reciprocable cylinder carriage 4. This shaft also has secured thereto at opposite ends thereof a pair of smaller pinions 45 which are in mesh with the teeth of stationary rack 46 fixed to the press frame. As illustrated in Fig. 4, the rack 46 extends parallel to and above the reciprocating rack 42. From the foregoing it will be appreciated that as rack 42 is reciprocated with the bed by the instrumentalities discussed above, it causes rotative or oscillating movement of gears 43. However, the smaller pinions 45 are, like gears 43, secured to shaft 44, hence rotatable with gears 43, so that as a result pinions 45 are caused to advance relative to the fixed stationary rack 46 with which they mesh, thereby advancing cylinder carriage 4 in a direction opposite the direction of advance of bed 2.

There will now be described the rotatable printing members or cylinders which are carried by the reciprocating carriage 4 and the manner in which they coact with the letter press type form 11 and transfer member 12 in performing the printing operation in accordance with the invention. These members consist of an offset cylinder 47 having an offset blanket 48 mounted thereon and an impression or printing cylinder 49 having a conventional tympan sheet 50 thereon. This cylinder likewise has associated therewith a suitable conventional gripper device 51 (Figs. 2 and 3) coacting with any desired automatic or semi-automatic sheet feeding mecha-

nism at the feed end of the press for properly receiving and securing the sheets 52 to the impression cylinder 49.

The shafts 53, 54 of the offset and impression cylinders 47, 49 respectively are each integrally provided with an eccentric 55 extending the length of the respective cylinders 47, 49, said cylinders being rotatable on these eccentrics in the operation of the press. At their ends shafts 53, 54 are carried in adjustable bearing blocks 56 on the cylinder carriage 4. The purpose of the aforesaid eccentric arrangement is to enable the cylinders 47, 49 to be elevated and lowered relative to the bed during the operation of the press, thereby enabling the offset cylinder 47 to engage the type form and offset surface 13 in one direction of movement of the cylinder carriage and to be elevated out of engagement therewith on the opposite movement. Likewise, it is necessary that the impression cylinder 49 cause the sheet to be printed to roll over offset surface 13 in the operative stroke of the cylinder carriage and to be elevated thereabove on the return stroke, so as to pass out of contact with said surface when no sheet to be printed is carried thereby.

The angular position of shafts 53, 54, hence of the eccentrics 55, is controlled by the tappet arms 58, 59 secured to the shafts 53, 54 respectively, externally of the bearing blocks. Tappet arm 58 has an internally directed lug 60 which is engageable with a fixed tappet 61 on the frame superstructure 3. The tappet arms 58, 59 are also provided with externally extending lugs 62, 63 respectively, engageable with adjustable tappet fingers 64, 65 respectively, which are secured to a rock shaft 66 extending longitudinally parallel to the side of the frame and journaled in brackets 67 thereon (Figs. 1 and 7). Tappet finger 64 is provided with an adjusting screw 641 having a lock nut 642 thereon. This adjusting screw regulates the lowering of the transfer cylinder 47 to conform with the size and character of the type form 11.

Shaft 66 has a laterally projecting rocker arm 68 secured thereto, this arm being interconnected by a rigid link 69 with one end of a cam follower lever 70 pivoted on the press frame at 71. The other end of this lever has a roller follower 72 thereon which is urged into engagement with a cam 73 rotatably mounted on the frame by means of a resilient tensioning member 74 secured to the frame and lever. Cam 73 is synchronized in its rotation with the reciprocatory movements of the bed and cylinder carriage, being rotatably actuated in any suitable manner from the main press shaft 23, and as the cylinder carriage reciprocates past the fingers 64, 65 the latter are shifted by shaft 66 into and out of position for engagement with the lugs 62 and 63. It will be noted that the arrangement of the cylinder journaling eccentrics 55, 55 is such that, with the respective cylinders in operative, lowered bed engaging position, the angular thrust on the cylinder tends to urge the eccentrics further and maintain the same in the cylinder lowering direction. This insures an effective printing contact of the printing members at all times, resulting in uniform clarity and sharpness of the final impression.

On the end of the shafts opposite the aforesaid control tappet arrangement, the shafts are provided with collars 731 (Fig. 2), having a lug 732 engageable at the opposite extremities of the angular movement of the shafts with stops 733 on the carriage. This position limits the angular

adjustment of the eccentric shafts in either direction. Coiled thrust springs 734 coact with collars 731 and the carriage to take up lost motion and assist in oscillating the eccentrics, and said springs 734 through a toggle-like action, as apparent from Fig. 2, operate to yieldingly retain the offset and the impression cylinder in either a depressed or an elevated position. The collar on the impression cylinder eccentric shaft has an inwardly extending tappet lug 735 coacting with a fixed tappet 736 on the superstructure 3 to elevate the impression cylinder for the return or non-printing stroke.

The transfer and impression cylinders 47, 49 are each provided with gears 75, 76 respectively, meshing with the reciprocating rack 42 as the latter is reciprocated to positively oscillate or rotate the cylinders. These gears are of a conventional split type, the parts of which are adapted to be angularly adjusted relative to one another to take up any lost motion in their meshing engagement with the rack. The form inking rolls 14 are positively driven by the reciprocating vibrator 16, this vibrator being driven through the agency of a gear thereon meshing with an idler which is in turn in meshing engagement with rack 42 on the bed.

In operation, let it be assumed that the bed and cylinder are moving in the direction of the arrows in Fig. 5. This is the return or non-printing stroke, in which offset cylinder 47 rolls over the form to pick up an impression therefrom. It has been placed in this lowered position by the engagement of control lug 62 with tappet 64 at the end of the preceding printing stroke. Cylinder 47 rolls over offset surface 13 during the return stroke to transfer its impression to the latter and after this happens the offset cylinder control lug 60 engages the fixed lug 61 to elevate the cylinder. During the aforesaid return stroke the impression cylinder 49 is maintained in elevated position by reason of the engagement of control lug 735 with fixed tappet 736 following the printing stroke.

When the impression cylinder has passed over offset surface 13 on the return stroke, the control lug 63 engages tappet 65 to lower the impression cylinder 49 for the succeeding printing stroke. Offset cylinder control lug 60 has previously engaged fixed tappet 61 on the return stroke to elevate the offset cylinder subsequent to its passage over offset surface 13, so that on the printing stroke the impression cylinder alone contacts the impression bearing offset surface 13. The impression cylinder never engages form 11.

Thus it will be understood that the two fixed tappets 61, 736 operate to elevate cylinders 47, 49 respectively, and the rockable tappets 64, 65 perform the lowering operation. These latter are rocked approximately in timed relation to the bed and carriage reciprocations so as to accomplish the aforesaid transfer engagements and disengagements in the manner described above, by cam 73 and elements actuated thereby.

The foregoing cycle is repeated on each printing and return stroke of the bed and cylinder carriage relative to one another, the offset blank 48 picking up a positive impression from the negative letter press type surface, transferring the same in reverse or negative to the flat offset surface 13, and the sheet on cylinder 49 receiving a positive offset impression therefrom. This impression is of uniform distinctness and sharpness; a washed-out, gray impression is impossible, and it is possible to set up quickly and

easily without extensive preparatory work, and without trial and error procedure subsequent thereto as by patching and the like, to enable a satisfactory impression to be had. The cylinders are positively driven at all times and no difficulty with blurring, smearing or the like is experienced. The press may be operated at very high speeds with uniformly satisfactory results.

In Fig. 3 the various successive impressions taking place in the printing cycle are illustrated. Thus the reverse or negative type face of form 11 is shown, the positive impression printed thereby, on offset blanket 48, the reverse or negative impression picked up therefrom by flat offset surface 13, and the final positive impression offset onto sheet 52 from this surface. Of course, it will be appreciated that the sheet would never be found in printed form at the feed end of the machine. The parts have been arbitrarily arranged in positions shown solely for the purpose of graphically describing the above successive operations. The provisions of this invention have been illustrated in association with a horizontal bed machine. However, it will be apparent that the inventive features are equally applicable to either a vertically or angularly arranged type machine, hence it is desired that the invention be not regarded as unduly limited in this respect.

An embodiment of the invention which incorporates the principles of the invention in a highly desirable manner has been illustrated and described, although it is clear that other embodiments within the intent of the invention will suggest themselves to those skilled in the art. It should be understood that the foregoing terminology is used only descriptively rather than in a limiting sense, and with full intention to include equivalents of the features shown and described, within the scope of the following claims.

Having thus described the invention what I claim as new and desire to secure by Letters Patent is:

1. In a bed and cylinder machine having a frame supporting a bed and a cylinder carriage simultaneously reciprocable in opposite directions, a relief type form and a flat offset surface on said bed in spaced relation to one another longitudinally of the direction of reciprocation, an offset cylinder rotatably mounted on said carriage having a resilient offset surface thereon engageable with said form and bed offset surface in one direction of relative reciprocation of the bed and carriage whereby to pick up an impression from said form and transfer the same to said bed offset surface, an impression cylinder rotatably mounted in said carriage and engageable with said bed offset surface in the opposite relative direction of reciprocation, said impression cylinder having means to secure a sheet thereon whereby the sheet picks up an impression from said bed offset surface, and means synchronized with the relative reciprocation of said bed and carriage for successively varying the vertical relationship of said cylinders to the bed as the relative reciprocation of the bed and carriage proceeds.

2. A machine for printing offset impressions from a negative type form, comprising a frame, a horizontal reciprocable bed carried by said frame having a relief type form and a flat offset surface thereon in longitudinally spaced relation, a cylinder carriage simultaneously reciprocable on said frame with said bed in a direction opposite the direction of reciprocation of the bed thereon, means for reciprocating said bed and

carriage in timed relation, a transfer cylinder rotatably mounted on said carriage, an impression cylinder rotatably mounted on said carriage, means for positively rotating said cylinders as the bed and carriage are reciprocated relative to one another, means for vertically shifting said cylinders relative to said bed in the reciprocation thereof, and means for synchronizing said last named means with the movements of the bed and carriage to rollingly engage the offset cylinder with said form and offset surface in one relative direction only of the reciprocation of the bed and carriage and to rollingly engage the impression cylinder with said offset surface only in the other direction.

3. A machine for printing offset impressions from a negative type form, comprising a frame, a bed carried by said frame having a relief type form and a flat offset surface thereon in longitudinally spaced relation, a cylinder carriage, means for reciprocating said bed and said carriage in opposite directions, a transfer cylinder rotatably mounted on said carriage, an impression cylinder rotatably mounted on said carriage, means for positively rotating said cylinders as the bed and carriage are reciprocated relative to one another, means for relatively shifting said cylinders and bed in reciprocation thereof, and means for synchronizing said last named means with the movements of the bed and carriage to rollingly engage the offset cylinder with said form and offset surface in one relative direction only of the reciprocation of the bed and carriage and to rollingly engage the impression cylinder with said offset surface only in the other direction.

4. In a printing machine for printing offset impressions from a relief printing form, in combination with a reciprocable bed having thereon a flat printing form of the above type and a flat offset surface, said bed travelling successively in opposite directions on printing and return strokes constituting a single printing cycle, a rotatable sheet carrying impression cylinder and a rotatable transfer cylinder mounted adjacent said bed and traversed by the latter in the reciprocation thereof, said offset cylinder including a resilient compressible offset blanket rollingly engageable with the form and compressible during said engagement to compensate for differences in the height of the printing surfaces on said form, means for inking said form in the reciprocation of the bed, said offset surface and form traversing said offset and impression cylinders respectively in the order named on the printing stroke, means controlled by the reciprocation of said bed for elevating the offset cylinder out of engagement with the form and offset surface and for relatively positioning the impression cylinder for rolling engagement of a sheet thereon with said offset surface on said printing stroke, and means controlled by the reciprocation of the bed for elevating the impression cylinder relative thereto out of engagement with said offset surface and lowering the offset cylinder for rolling engagement with the form during the return stroke, whereby a complete printing cycle is performed in the printing and return strokes, said offset cylinder receiving an impression from the form on the return stroke and transferring said impression to said offset surface, the sheet on said impression cylinder receiving an impression from said surface on the printing stroke during which the offset cylinder is elevated relative to said surface.

5. In a printing machine for printing offset impressions from a relief printing form, in combination with a reciprocable bed having thereon a flat printing form of the above type and a flat offset surface, said bed travelling successively in opposite directions on printing and return strokes constituting a single printing cycle, a rotatable sheet carrying impression cylinder and a rotatable transfer cylinder mounted adjacent said bed and traversed by the latter in the reciprocation thereof, said offset cylinder including a resilient compressible offset blanket rollingly engageable with the form and compressible during said engagement to compensate for differences in the height of the printing surfaces on said form, means for inking said form in the reciprocation of the bed, said offset surface and form traversing said offset and impression cylinders respectively in the order named on the printing stroke, means controlled by the reciprocation of said bed for elevating the offset cylinder out of engagement with the offset surface and for positioning the impression cylinder for rolling engagement of a sheet thereon with said offset surface on said printing stroke, means controlled by the reciprocation of the bed for elevating the impression cylinder relative thereto out of engagement with said offset surface during the return stroke, and means for raising and lowering said offset cylinder relative to the bed to successively receive an impression from the form and transfer the same to said surface on one stroke, and to miss contact with said surface on the other stroke, whereby a complete printing cycle is performed in the printing and return strokes, said offset cylinder receiving an impression from the form and transferring said impression to said offset surface, the sheet on said impression cylinder receiving an impression from said surface on the printing stroke.

6. In a printing machine for printing offset impressions from a relief printing form, in combination with a printing form of the above type and an offset surface, a rotatable sheet carrying impression cylinder and a rotatable transfer cylinder, means for reciprocating said form and surface relative to said cylinders successively on opposite printing and return strokes, means for inking said form, said offset surface and form traversing said offset and impression cylinders respectively in the order named on the printing stroke, means for relatively shifting the offset cylinder out of engagement with the offset surface and for relatively positioning the impression cylinder for rolling engagement of a sheet thereon with said offset surface on said printing stroke, means for relatively shifting the impression cylinder out of engagement with said offset surface during the return stroke, and means for raising and lowering said offset cylinder relative to the bed to successively receive an impression from the form and transfer the same to said surface on one stroke, and to miss contact with said surface on the other stroke, whereby a complete printing cycle is performed in the printing and return stroke, said offset cylinder receiving an impression from the form and transferring said

impression to said offset surface, the sheet on said impression cylinder receiving an impression from said surface on the printing stroke.

7. In a bed and cylinder machine having a frame supporting a bed and cylinder carriage reciprocable relative to each other, a relief type form and a flat offset surface on said bed in spaced relation to one another longitudinally of the direction of reciprocation, an offset cylinder rotatably mounted on said carriage having a resilient offset surface thereon engageable with said form and bed offset surface in one direction of relative reciprocation of the bed and carriage, means for automatically varying the paths of travel of said offset cylinder and bed relative to each other during each work cycle of movement thereof, whereby to pick up an impression from said form and transfer the same to said bed offset surface, and an impression cylinder rotatably mounted in said carriage and engageable with said bed offset surface only in the opposite relative direction of relative reciprocation, said impression cylinder having means to secure a sheet thereon whereby the sheet picks up an impression from said bed offset surface.

8. In a bed and cylinder machine having a pair of printing member supports simultaneously operable in opposite directions, a flat relief type form and a flat transfer surface mounted in spaced relation to one another on one of said supports, a rotary offset surface and a rotary sheet carrying member on the other support, said offset surface being successively engageable with said form and transfer surface in the relative movement of said supports to pick up an impression from said form and transfer the same to said transfer surface, said sheet carrying member engaging a sheet thereon with said transfer surface whereby said sheet picks up an impression from said transfer surface, and means synchronized with the relative movement of said supports for effecting engagement of said rotary offset surface with said flat form and flat transfer surface in one stroke of the form and transfer surface and disengagement thereof in the opposite stroke and for effecting engagement of said rotary sheet carrying member with said flat transfer surface in one stroke of said transfer surface and disengagement in the opposite stroke.

9. In a bed and cylinder machine having a pair of printing member supports simultaneously operable in opposite directions, a flat relief type form and a flat transfer surface mounted in spaced relation to one another on one of said supports, a rotary offset surface and a rotary sheet carrying member on the other support, said offset surface being successively engageable with said form and transfer surface in the relative movement of said supports to pick up an impression from said form and transfer the same to said transfer surface, said sheet carrying member engaging a sheet thereon with said transfer surface whereby said sheet picks up an impression from said transfer surface.

CHARLES L. LOW.
